E. WINKLER

CHILD'S VEHICLE

Filed Mar. 7, 1922

UNITED STATES PATENT OFFICE.

EDMUND WINKLER, OF BROOKLYN, NEW YORK, ASSIGNOR OF ONE-HALF TO SADIE HAJDU, OF BROOKLYN, NEW YORK.

CHILD'S VEHICLE.

Application filed March 7, 1922. Serial No. 541,730.

To all whom it may concern:

Be it known that I, EDMUND WINKLER, a citizen of Czecho-Slovakia, residing at Brooklyn, in the county of Kings and State 5 of New York, have invented certain new and useful Improvements in Children's Vehicles, of which the following is a specification.

This invention relates to toy vehicles the 10 main object being to provide a toy which is both amusing and instructive and also to provide means for exercising the limbs of a child in a manner pleasant to him.

These and other objects will become apparent in the description below in which characters of reference refer to like-named parts in the drawing.

Referring briefly to the drawing Figure 1 represents a side elevational view of the 20 toy.

Figure 2 is a front elevational view of the same.

Figure 3 is a top plan view of the front swivel yoke connected to the body brace.

Figure 4 is a side view of the rear axle and shows the means for journalling the same beneath the legs.

Describing the drawing more in detail, the numeral 1 represents the broad rounded 30 back of an animal, in this instance a dog, having a head 2, upstanding ears 3, and fore and rear legs 4 and 5 respectively. These animals are of the usual type having a fur-like coat and stuffed with excelsior or 35 the like.

Hind legs 5 are rigidly connected to the body while the fore legs 4 are detached from it in the region of the chest a portion of which, indicated by 6, occurs below the 40 horizontal division. The contacting surfaces of both the body and fore leg members are each provided with a metallic plate 7 which forms a broad flat supporting surface for the animal.

45 A yoke 8 secured between the legs 4 projects slightly below the latter and forms a bearing for pedal shaft 9 which has retaining collars 10 securely pinned thereto. Each end of the pedal shaft 9 has a square extension which receives a pedal crank 11 having a foot pad 12 swivelly attached to its outer end. The pedal crank at the other end of the shaft extends therefrom in the opposite direction.

A rubber tired wheel 13 is fixed to shaft 55 9 and forms a means of locomotion for the toy when the pedal cranks are manipulated.

An additional means of securing the shaft 9 to the fore legs 4 is provided by wires 14 which extend upwardly into said legs and 60 are slightly curved at the upper end and are wound about the shaft 9 after the fashion of a coil spring and as illustrated in Figure 4.

A vertical steering rod 15 fixed to yoke 8 65 extends upwardly and is rotatable within the sleeve 17 secured to upper plate 7 and within the body of the animal. Handle bar 16 pinned to the upper end of rod 15 is adapted to rotate or swivel the yoke 8, when 70 manipulated.

A pair of rear wheels 18 mounted on an axle 19 are secured to the hind legs 5 by wires 20 encircling the said axle as indicated by numeral 21. These wires 20 extend upwardly within the hind legs and are then bent into a horizontal direction from whence they are twisted about each other and encircle sleeve 17 at their other end. 75

A child when using the toy seats itself 80 upon the back of the animal, placing the feet upon the pedal foot pads 12 alternately pushing on each.

When a change in direction of travel is desired, handle bar 16 is turned into the 85 required direction thereby facing wheel 13 in a new direction without retarding the forward travel of the toy.

It is to be understood that certain changes such as the use of various types and sizes 90 of animals may be made without departing from the spirit and scope of the invention.

I claim:

A vehicle toy comprising an animal body having rotatable fore legs, a yoke between 95 said legs having a shaft rotatable therein, a wheel in said yoke, a vertical steering rod secured to said yoke, a sleeve in the animal body adapted to receive said steering rod, a handle bar on said rod, an axle, a pair 100 of wheels on said axle, a twisted wire encircling said sleeve and extending backwardly downward and securing the axle to the hind legs substantially as described, and means for propelling the toy. 105

In witness whereof, I affix my signature.

EDMUND WINKLER.
